CLAIM

The ornamental design for protector for outboard motor fuel hoses, as shown and described.

DESCRIPTION

FIG. 1 is a right perspective view of a protector for outboard motor fuel hoses embodying my new design;

FIG. 2 is a top plan view thereof;

FIG. 3 is a front elevational view thereof;

FIG. 4 is a rear elevational view thereof;

FIG. 5 is an end elevational view thereof, the opposite end being a mirror image thereof;

FIG. 6 is a bottom plan view thereof;

FIG. 7 is a right perspective view of a modified form of the protector for outboard motor fuel hoses shown in FIGS. 1 thru 6; and,

FIG. 8 is a right perspective view of another modified form of the protector for outboard motor fuel hoses, shown in FIGS. 1 thru 6.

*Fig. 1**Fig. 2**Fig. 3**Fig. 4**Fig. 5**Fig. 6*

Fig. 7

Fig. 8
